ANTENNA MOUNTABLE IN SMALL SPACES

Arthur Dorne, Mineola, N. Y., David Lazarus, Chicago, Ill., and Herbert P. Minot, Belmont, Mass., assignors to the United States of America as represented by the Secretary of War

Application April 30, 1946, Serial No. 665,990

5 Claims. (Cl. 250—33)

1

This invention relates to electrical apparatus and more particularly to improvements in antennas.

In the design of antennas for aircraft installations, it is desired to minimize wind resistance. Previous antenna designs have in general required a substantially hemispherical radiating aperture. Streamlined antenna stubs (one-half of a dipole above a reflecting plane) and various special antennas generally mounted within a blister (hemispherical projection) on the aircraft have been used. Such designs usually cannot be mounted within the confines of the aircraft surfaces and require some external projection on the surface of the aircraft. This difficulty is associated principally with the large radiating aperture required.

An object of the present invention is to provide an antenna system having a relatively small radiating aperture and adapted to be mounted within the confines of a curved metallic surface.

A further object of the present invention is to provide such an antenna system with fairly broad radiation patterns in both horizontal and vertical planes.

A further object of the present invention is to effectively match said antenna system to its feed line.

Other objects and advantages of the invention will be apparent during the course of the following description.

The present invention may best be classified as a radiator of high frequency electromagnetic energy. It is constructed as a fairly short section of parallel plate transmission line which is short-circuited at one end. Disposed within the waveguide space of this transmission line is an antenna stub. The term "stub" denotes a radiating element having an effective electrical length of a quarter wavelength or less and mounted above a reflecting plane. This antenna stub is capacitively loaded in order to increase its electrical length and to more closely match its radiation resistance to the characteristic impedance of its feed line. By means of this capacitive loading, the overall size of the antenna system is greatly reduced. The parallel plate transmission line may be shaped to conform with the outline of a curved surface such as the leading edge of the wing or the wing tip of an airplane, and the entire antenna system may be completely enclosed within the confines of the aircraft wing surface in such a manner as to not disturb the streamlined surface of that member.

In the accompanying drawing forming a part of this specification,

Fig. 1 is a broken-away isometric view of one embodiment of the present invention;

Fig. 1(a) is a simplified top view of Fig. 1, drawn to a reduced scale;

Fig. 2 is a simplified top view of another em-

2

bodiment of the present invention which utilizes a slightly different form of capacitive loading; and

Fig. 3 is a simplified top view of a third embodiment of the present invention which utilizes still another method of capacitive loading.

In Fig. 1, wherein is shown one possible embodiment of the present invention, numerals 10 and 11 designate two substantially parallel conducting plates which in effect form a section of parallel plate transmission line. A conducting back plate 12 is disposed substantially perpendicularly to parallel plates 10 and 11 and terminates the transmission line formed by plates 10 and 11 at one end thereof. The edges of plates 10 and 11 may be shaped to conform to a curved surface such as the leading edge of the wing or the lateral wing tip of an aircraft. Disposed within the waveguide space formed by plates 10, 11 and 12 is a conical antenna stub 13 (best seen in Fig. 1(a)) having a capacitive loading element 14. Capacitive loading element 14 is here shown as a U-shaped stove pipe member but other capacitive loading means may be used if desired. The capacitive loading element 14 is supported and maintained rigidly with respect to the plates by means of insulating supports 15 which extend between end closure plates on capacitive loading element 14 and the back plate 12. The antenna stub 13 is fed by a coaxial line 16 having its inner conductor 17 electrically connected to stub 13 and its outer conductor 18 electrically connected to conducting plate 10.

Fig. 1(a) shows a simplified top view of Fig. 1 drawn to a reduced scale, and is included to more clearly illustrate the use of alternate types of antenna stubs and capacitive loading means. In Fig. 2 a cone antenna 19 replaces the antenna stub 13 and capacitive loading element 14 of Fig. 1(a). In Fig. 3 a somewhat enlarged conical antenna stub 13' is utilized instead of antenna stub 13 of Fig. 1(a). The capacitive loading is effected by a conducting plate 14'.

The waveguide formed by plates 10, 11 and 12 is the actual radiator of electromagnetic energy. Electromagnetic waves may be set up in this waveguide space by a capacity-loaded antenna stub. This exciting antenna may be the conical antenna stub 13 and capacitive loading element 14, the cone antenna 19, or the conical antenna stub 13', and capacitive loading plate 14'. The capacitive loading serves to increase the electrical lengths of the antenna stub and to more effectively match it to the coaxial line 16. The polarization of the radiated electromagnetic energy is parallel to the axis of the antenna stub (i. e. to the axis of the cone) and the parallel plates 10 and 11 propagate electromagnetic energy therebetween in the transmission line mode. These radiators are fairly broad-band and the

radiation patterns are broad and symmetrical in both horizontal and vertical planes.

Such an antenna system may readily be built within the confines of a curved surface having a radius of the order of an eighth wavelength. Because of its shape and small size, it may readily be placed within the leading edge of the wing or the lateral wing tip of an aircraft, where other types of antennas would not be practical. The choice between the two locations would in general be determined by the desired polarization of the emitted radiation. The polarization will be parallel to the axis of the conical stub. For horizontal polarization the antenna system would generally be mounted within the leading edge 15 of the aircraft wing, with the curved edges of plates 10 and 11 conforming to the curved surface of the leading edge. For vertical polarization the antenna system would generally be turned on its side and mounted in the wing tip of the aircraft. However, in the majority of applications the antenna system may be mounted in the position shown or turned on its side in either the leading edge of the aircraft wing or in the wing tip, allowing the attainment of the 20 desired direction of polarization in either location.

While the present invention has been described emphasizing its particular applicability for aircraft installation, the invention is not limited thereto and may be applied as well in other installations which permit its use.

It will be apparent that there may be deviations from the invention as described which still fall fairly within the spirit and scope of the invention.

What is claimed is:

1. A radiator of high frequency electromagnetic energy including two conducting plates lying wholly in substantially parallel planes, a third conducting plate disposed substantially perpendicularly to and connecting said parallel plates at one end thereof, said parallel plates being insulated from one another except for the connection of said third plate, said plates defining therebetween a transmission line, a conical antenna stub disposed within said transmission line and having its axis substantially perpendicular to said parallel plates, said antenna stub having a length less than a quarter the length of the operating wave, capacitive loading means being electrically connected to said antenna stub for increasing the electrical length thereof, and a coaxial line external to said transmission line, the center conductor of said coaxial line being electrically connected to said antenna stub and the outer conductor being electrically connected to said conducting plates.

2. A radiator of high frequency electromagnetic energy including two conducting plates lying wholly in substantially parallel planes, a third conducting plate disposed substantially perpendicularly to and connecting said parallel plates at one end thereof, said parallel plates being insulated from one another except for the connection of said third plate, said plates defining therebetween a transmission line, a cone antenna disposed within said transmission line, and a coaxial line external to said transmission line extending through one of said parallel plates and having its inner conductor electrically connected to said cone antenna and its outer conductor electrically connected to said one parallel plate.

3. A high frequency radiator adapted for

mounting in a small space comprising a pair of plates lying wholly in substantially parallel planes to form a transmission line, a conducting plate mounted perpendicular to said parallel plates and short-circuiting said parallel plates at one end, said parallel plates being insulated from one another except for the connection of said perpendicular plate, said plates being shaped at the end remote from said one end to fit in the space in which said radiator is to be mounted, a conical stub antenna mounted in the space between said parallel plates and oriented to feed high frequency energy to said parallel plates in the transmission line mode, a coaxial line extending through one of said parallel plates and having an outer conductor connected to said one parallel plate and an inner conductor connected to said antenna for feeding the high frequency energy thereto, and a conductor connected to said antenna and capacitively coupled to said parallel plates for increasing the electrical length of said antenna.

4. A high frequency radiator comprising a section of transmission line composed of two conductive plates lying wholly in substantially parallel planes, said transmission line being short-circuited at one end by another conductive plate lying wholly in a plane perpendicular to said conductive plates and opened on all other sides, means coupled to said line for feeding high frequency electromagnetic energy thereto in the transmission line mode, said feeding means including a radiating conductor mounted in the space between said parallel plates of said transmission line and means capacitatively coupling said radiating conductor and said transmission line.

5. A high frequency radiator comprising three conductive plates, two of said plates lying wholly in substantially parallel planes, the third one of said plates being mounted transversely to said parallel plates and lying wholly in a plane substantially perpendicular thereto and short-circuiting said parallel plates at one end thereof, said parallel plates being insulated from one another except at said short-circuited end and forming a transmission line open circuited at the end remote from said one end for radiating energy from said remote end, means coupled to said transmission line for feeding high frequency electromagnetic energy thereto in the transmission line mode, said feeding means comprising a conical radiating conductor oriented in the space between said parallel plates to feed said plates with high frequency electromagnetic energy in the transmission line mode, and an additional conductor connected to said radiating conductor and capacitatively coupled to said parallel plates for increasing the effective electrical length of said electrical conductor.
